[57] CLAIM

The ornamental design for multiplexed electrostatic copier having plural scan stations and common development, as shown and described.

DESCRIPTION

FIG. 1 is a perspective view of a multiplexed electrostatic copier having plural scan stations and common development, showing my new design;

FIG. 2 is a top plan view thereof;

FIG. 3 is a side elevational view, taken in the direction of line 3—3, shown in FIG. 2.

The surface underneath the scan stations is substantially planar and unornamented. All four stations are identical to the one which is fully disclosed in FIG. 1.

FIG. 1
